Fig: 2.

BY

Henry H. Mason

ATTORNEY

UNITED STATES PATENT OFFICE.

HENRY H. MASON, OF SPRINGFIELD, VERMONT.

MOP-HEAD.

SPECIFICATION forming part of Letters Patent No. 357,846, dated February 15, 1887.

Application filed June 17, 1886. Serial No. 205,390. (No model.)

To all whom it may concern:

Be it known that I, HENRY H. MASON, of Springfield, in the county of Windsor and State of Vermont, have invented a certain new and 5 useful Improvement in Mop-Heads, of which I declare the following to be a full, clear, and exact description, reference being had to the accompanying drawings, forming a part of this specification.

10 This invention has for its object an improvement in mop-heads; and the invention consists in a mop-head constructed and combined in the manner and for the purpose with particularity hereinafter shown, described, and claimed.

15 In the accompanying sheet of drawings, Figure 1 is a side view of my mop-head with a mop-rag secured therein. Fig. 2 is a section in the line *x x*, Fig. 1.

Similar letters of reference indicate like 20 parts in both figures.

The well-known mop-head is improved, simplified, and cheapened by my invention, which consists of a mop-head with a tubular screw, A—that is, the shank *a* of the screw is made 25 hollow or tubular, with threads *b* formed on its outer surface. To the lower end of the screw is fixed in any way desirable a cross-head or fixed jaw, B, its two ends terminating in guides *c* and *d* at right angles to the cross-head.

30 A movable jaw, C, is next provided with a central opening, through which passes the shank *a* of the screw A. The ends of this movable jaw are recessed to receive the guides *c* and *d*. On the screw A is fitted a nut, D, immediately 35 above the jaw C, and into the tubular screw A may be fitted a haft, E, which completes the

general construction of my mop-head. It is utilized by inserting between the cross-head B and jaw C a mop-cloth, F. This cloth is held in position by screwing down the nut D, 40 which forces the jaw C in close contact with the cloth F and clamps it between the jaw C and the cross-head B. The cloth so clamped to the mop-head is used in the ordinary manner.

45 From the foregoing description of the construction and operation of my mop-head it will be obvious to one familiar with mop-heads that my mop-head is simple, strong, light, and comparatively inexpensive, and it possesses the very great advantage of easily securing the 50 mop-cloth in place without requiring much effort, and of affording by its tubular screw a ready means of attaching the handle to the head. All the metal parts may be made from cast-iron and be fitted together without subsequent fitting.

55 Having now described my invention, what I claim as new, and desire to secure by Letters Patent, is—

A mop-head constructed with the following 60 elements in combination: a tubular screw, A, with a cross-head, B, having guides *c* and *d* fixed thereto, a movable jaw, C, through which passes said screw A, and which is guided by the guides *c* and *d*, and a screw-nut, D, fitted on 65 the screw A, whereby the jaw C may be operated, as and for the purpose described.

HENRY H. MASON.

In presence of—

G. M. PLYMPTON,
D. A. CARPENTER.
